VACUUM SPOTTING BOARD

Frank H. Richterkessing, Jefferson County, near Louisville, Ky., assignor to W. M. Cissell Manufacturing Company, Louisville, Ky., a corporation of Kentucky

Application March 6, 1950, Serial No. 147,943

6 Claims. (Cl. 68—240)

1

This invention relates to a vacuum spotting board of the class which embodies a main spotting board for supporting various garments, fabrics and the like during spotting operations thereon, and an auxiliary or sleeve board for supporting sleeves or other relatively small sections of such garments or fabrics, in position for spotting operations thereon.

A primary object of the invention is to provide a construction embodying such a main spotting board and sleeve board wherein the sleeve board is swingable parallel to the work supporting surface of the main board to and from an operative position, and such movement serves to operate a valve which functions to disconnect simultaneously the suction line of one board from a suction device or passage while connecting the suction line of the other board thereto.

A further object is to provide a valve of novel construction for transferring the suction from one to the other of said boards in accordance with the position of the sleeve board.

A still further object is to provide in such a valve a resilient element functioning both as a fluid seal between relatively movable parts of the valve body, and as a compression spring resiliently urging said movable parts into substantially fluid tight engagement with cooperating valve elements.

A still further object is to render the supporting leg or standard for these spotting boards vertically extensible, whereby the height of the boards may be adjusted as desired for the convenience and comfort of the operator, while at the same time providing in said standard a fluid tight trap for interposition in the vacuum line between said boards and any usual suction device, to remove solvents, foreign matter or soil removed by the solvent and condensate from the suction line before such matter is drawn through the suction device with possible deleterious effects.

In this application I show and describe only the preferred embodiment of my invention, simply by way of illustration of the practice thereof as by law required. However I recognize that the invention is capable of other and different embodiments and that the several details of the invention may be altered in various manners, all without departing from my invention. Accordingly, the drawings and description herein are to be considered as merely illustrative and not as exclusive.

In the accompanying drawings:

Figure 1 represents a perspective view of a vacuum spotting board in accordance with my invention;

Figure 2, an end elevation of the spotting board shown in Figure 1;

Figure 3, a front elevation thereof partly in section on the line 3—3 of Figure 2, looking in the direction of the arrows;

2

Figure 4, a detail sectional view on the line 4—4 of Fig. 3, showing the arrangement of the steam chest with its several control valves;

Figure 5, an enlarged plan view of the spotting board of Figure 1 with the sleeve board swung to inoperative position and showing same in broken lines as it will appear when in operative position;

Figure 6, a detail cross-section on the line 10 6—6 of Figure 5, looking in the direction of the arrows and showing details of the suction control valve construction;

Figure 7, a cross-section on the line 7—7 of Figure 5, looking in the direction of the arrows;

Figure 8, a section on the line 8—8 of Figure 5, looking in the direction of the arrows;

Figure 9, a section on the line 9—9 of Figure 5, looking in the direction of the arrows; and,

Figure 10, an enlarged fragmentary section of the suction control valve and related structure, same being in the same plane as that in which the corresponding parts are shown in Figure 3.

Referring now in detail to the accompanying drawings, the reference character 1 therein designates a usual spotting board base of cast metal construction having a supporting column or standard 2 projecting upwardly therefrom on which is supported a main spotting board 3 and a horizontally swingable sleeve board 4, which 25 may be swung either to the operative position indicated above the main board 3 as indicated in broken lines in Figure 5, or to the inoperative position away from and out of registry with the main board 3 as shown in full lines in Figure 5. In accordance with usual practice, a tray 5 may 30 also be supported on the standard 2 to support the garments or fabrics above the floor.

In the form shown, the base is provided with a plurality of control pedals 6, 7 and 8 which are 35 separately operatively connected through usual mechanical linkages with valves 6a, 6b, and 7', 8' respectively to control the flow of various fluids through said valves from a chamber 9 which may be mounted on the base 1 as shown. The major portion of chamber 9 constitutes a steam chest which is adapted to be supplied with steam under pressure through suitable pipes (not shown) connected to the inlet and outlet openings 10 and 12 respectively shown in Figure 2.

The valves 6a and 6b are controlled by the foot 40 pedal 6 in known manner to supply either dry steam or various degrees of moist or wet steam through a flexible tube 13 to a usual steam spotting or spray gun 14 which is adapted for use in usual manner in steam spotting operations on garments supported on either of the boards 3 or 4.

It will be seen that the steam valve 6a communicates directly with the upper portion of the steam chamber to have only steam supplied therethrough, while the water valve 6b (see Figure 3) 45 controls the discharge of water through a stand-

pipe 15 which has its lower end at a level below the surface of the condensate which will normally form in the bottom of chamber 9, to be forced upwardly through said stand pipe 15 and valve 6b when the latter is opened.

The two valves 6a and 6b have their discharge sides connected by a pipe 16 the medial portion of which is connected through a transverse pipe 17 to the flexible tube 13 leading to the spray gun 14. Thus whenever desired, water may be injected at any desired rate through the valve 6b into the flow of steam to the spray gun from valve 6a. Since, as shown in Figures 1 and 2, the actuating arm of the water valve 6b normally assumes a closed position spaced slightly below the actuating arm of steam valve 6a, and only the latter is directly connected through the linkage 6c to control pedal 6, the pedal 6 may be depressed to such a degree as to open only the steam valve 6a and thus permit only a flow of relatively dry steam to the spotting gun 14, or it may be depressed sufficiently to cause engagement between the actuating arms of the respective valves 6a and 6b to thereby move the actuating arm of valve 6b downwardly and thereby cause water to be injected into the steam.

The valve 1', when opened by depression of foot pedal 7 permits a flow of steam under pressure from the chamber 9 through said valve 1' and a pipe 18 communicating therewith to a usual steam injector 19 exemplifying any of various usual means which may be employed to create a suction or partial vacuum through the boards 3 and 4, as hereinafter described.

A small portion of the chamber 9 is preferably formed as a compressed air chamber or compartment 20 (Figure 2) in accordance with usual practice to be supplied with heated compressed air through a suitable inlet 60. In the instant embodiment, the valve 8' in communication with this air compartment 20 may be opened as desired by depression of the pedal 8 to permit air to flow therefrom for use in any usual drying device. I find it convenient to render the spotting gun 14 capable of use as a dryer, and to this end prefer to connect the discharge line 21 from the air valve 8' to the pipe 17 to which the spray gun tube 13 is connected.

The standard 2 is preferably rendered vertically extensible so that the spotting boards 3 and 4 may be positioned at levels most comfortable and convenient for operators of varying heights and preferences, and also is preferably formed with a fluid tight solvent chamber or trap 22 therein to be interposed in the suction passage between the suction device or injector 19 and the boards 3 and 4. The function of such a trap 22 is to remove solvents, condensate, lint and other foreign substances from the air drawn through the boards 3 and 4, to prevent such matter from being drawn into the suction device with possible deleterious results.

To this end, the standard 2 of the preferred embodiment is formed of two tubular relatively telescopically disposed standard sections 2a and 2b respectively which may be secured in any desired position within their range of adjustment by means such as a set screw 23 threaded through the wall of the lower outer section 2a into engagement with the movable upper section 2b. With such arrangement, a partition P across the interior of the lower section 2a defines the bottom of the trap 22 which is of course disposed at a level considerably below the level of the passage 24 leading from the trap to the low pressure side 75

of the injector 19. If desired a suitable outlet or drum cock D may be employed in connection with the trap 22 to drain moisture therefrom into a receptacle R supported on the base 1.

In this arrangement, the inner standard section 2b will generally project downwardly past the injector passage 24, and it has accordingly been found advisable to provide a substantial annular space between the walls of the respective sections 2a and 2b to avoid obstructing said injector passage 24. Therefore, the inner section 2b is formed of relatively smaller diameter than the outer section 2a and is received in an annular inwardly projecting flange 25 adjacent the upper end of said outer section 2a. An annular gasket 26 of rubber or other suitable packing material is cemented or otherwise suitably secured above the flange 25 between the relatively spaced walls of the sections 2a and 2b to prevent leakage of air into the vacuum chamber or trap 22.

The movable upper standard section 2b has its upper end covered by a preferably integral lower valve plate 27 having a smooth horizontally presented upper surface and formed with a suction port 28 extending medially therethrough and thereby communicating with the suction device or injector 19 through the trap 22.

The main spotting board 3 mounted on the standard 2 is of conventional construction, embodying a usual upwardly opening pan 29 preferably of stainless steel construction, a substantially flat work surface 30 of liquid impervious stainless material such as vitrolite, glass, porcelain or the like supported on and covering said pan for the major portion of its length, but terminating short of the free end thereof. Said free end is arranged substantially as disclosed in the Shoop et al. Patent 2,399,576 to provide a suction means for removing the solvent and absorbed foreign matter from garments and other fabric articles placed thereover. Accordingly, as shown in Figure 9, the said end is provided with a porous cover including a rigid perforated cover plate 32, which may be of stainless steel, and a porous mesh covering 33 which should be of stainless steel screen. Such solvent and foreign matter is drawn through this porous cover into the vacuum or suction line 34 extending longitudinally within the board 3 with its intake opening 35 disposed directly beneath and preferably centrally of the said porous cover 32, 33, all as best shown in Figures 3 and 5. Solvent or foreign matter entering chamber 35 is drawn or drained into the suction line 34 through openings 29A in the opposite walls of suction line 34, as indicated in Fig. 9.

Communicating at all times with the vacuum line 34 is an evacuation port or opening 36 which extends through the bottom of the pan 29 and an upper valve plate 37 connected thereto and in spaced parallel relation above the lower valve plate 27. In the instant embodiment the upper valve plate 37 is fixedly secured directly to the lower plate 27 in properly spaced horizontal relation thereabove, as by bolts 38 having spacer sleeves 39 therearound and abutting against both of said plates. The main board 3 is thus supported on the upper plate 37.

Not only does the vacuum or suction line 34 of the board 3 communicate with the evacuation port 36, but it is also desirable, as shown in Figure 8, to provide a small drain passage 40 from the drain pan 29 into said port, to thus carry away liquids which may enter the pan 29 exteriorly of the vacuum line 34.

A movable valve element or body 42 is pivotal-

ly mounted between the valve plates 27—37, as at 43, for swinging movement between the opposed horizontal surfaces of said plates and across the ports 28 and 36 therein, between limits which may be defined by transversely opposed spacer sleeves 39.

Carried by and swingable with said valve element 42 is the hollow supporting arm 44 having an upwardly directed free end portion 45 on which is fixedly mounted the swinging sleeve board 4 10 at a level somewhat above the main board 3.

Such a sleeve board 4, except for being of relatively smaller size, is constructed and functions in substantially the same manner as the main board 3. Accordingly the sleeve board is provided 15 at its free end with a porous work surface consisting of the perforated cover plate 32' and screen mesh 33' thereon, beneath which is disposed the intake opening 35' of a vacuum line 34' extending beneath the work surface of said sleeve board and communicating through the bottom thereof with the hollow interior of the swinging arm of pipe 44. The arm 44 in turn communicates with a downwardly opening passage or port 46 in the lower horizontal face of the valve element 42.

The port or passage 46 opens at such a location in the valve element 42 as to register with the suction port 28 of the lower valve plate when the sleeve board 4 is swung to operative position above the main board 3, as shown in broken lines in Figure 5. In such position the valve element will abut against one of the spacer sleeves 39 which thus serves as a stop to accurately determine said position.

As is clearly shown in Figures 3 and 6 of the drawings, a through port or passage 47 extends completely through the valve element 42 between the upper and lower horizontal faces thereof in a location to establish communication between the suction port 28 in the lower valve plate and the evacuation port 36 in the upper valve plate, when the sleeve board 4 is swung to its inoperative position out of vertical registry with the main board 3, as indicated in full lines in Figure 5.

While the valve element 42 may be constructed in any of various manners, considering the invention from its broader aspects, I prefer to form such element in the novel manner hereinafter described to minimize the leakage of air therethrough into the vacuum passages. According to such preferred construction, as best shown in Figures 6 and 10, the valve element 42 comprises two separate sections 48 and 49 respectively, the upper section 49 being guided for vertical movement on the lower section 48 by means of an integral sleeve 50 slidable in a bore 51 through the lower section, the sleeve 50 and bore 51 together defining the through passage 47 aforementioned. In order to permit free vertical movement of the upper section 49 into engagement with the upper plate 37, the supporting 50 hollow arm 44 for the sleeve board is secured only to the lower section 48 and the pivotal connection 43 is similarly made only between the lower section 48 and the lower valve plate 27. An annular gasket 52 of rubber or other resiliently compressible material is disposed about the sleeve 50 and compressed between the two sections as they are placed between the respective plates 27 and 37, so that the gasket will tend to resiliently urge these two sections into engagement with their respective valve plates 27 and 37. Obviously the gasket 52 will function as a fluid seal to prevent leakage of air into the port or passage 47 between the respective sections 48 and 49.

In order to close the evacuation port 36 in the upper valve plate 37 and thereby prevent leakage of solvents therefrom during use of the sleeve board, it has been found desirable to provide the upper valve section 49 with a lateral extension 53 which, if desired may have a vertical projection 54 slidably disposed in a recess in the lower section 48, as shown in Figure 8, to prevent relative rotary movement of the two sections.

In the operation of a spotting board in accordance with the invention, where it is desired to use the main spotting board 3 the sleeve board 4 is swung to the inoperative position shown in full lines in Figure 5, thereby moving the valve element 42 so that its through passage 47 establishes communication between the suction port 28 and the evacuation port 36 for the main board. Following this, garments or other fabric articles may be placed on the main work surface 29 thereof and spotted either by usual chemical solvents or by steam and or water applied through the spotting gun 14. Following this, the spotted portions of the garment may be placed on the porous surface 33 of the board. Actuation of the suction device 19 by depression of its control pedal 7 will then create a downward suction through said spotted portions and porous surface 33 to draw the moisture from the material into the vacuum line 34. The drying process may of course be expedited by applying hot air to the material by means of the spray or spotting gun 14, the discharge of air from said gun being controlled by depression of the foot pedal 8.

Where it is desired to use the sleeve board 4, it may be swung into the operative position illustrated in Figure 1 and, in broken lines in Figure 5. It will be seen that this swings the valve element 42 to such a position as to place the vacuum line 34' of board 4 in communication through the valve 42 and vacuum chamber or trap 22 with the suction device or injector 19. Consequently, depression of the foot pedal 7 will create a suction through the sleeve board, so that it may be used in the same manner as the main board.

I claim:

1. In a vacuum spotting board, a vacuum chamber and means for maintaining a partial vacuum therein, a horizontal plate mounted on said chamber and having a suction port therethrough communicating with said chamber, a main spotting board mounted in spaced relation above said plate and having a vacuum line operatively associated therewith, means connected to the under surface of said board defining a smooth horizontal surface spaced above said plate, said surface having an evacuation port opening downwardly therethrough from said vacuum line, in combination with a valve element pivotally mounted between said plate and said surface and in snug engagement with each for swinging movement across said ports, a sleeve board carried by said valve element for swinging movement therewith between an operative position above said main board and an inoperative position out of vertical registry with said main board, a vacuum line being operatively associated with said sleeve board, said valve element having a fluid passage therethrough located to establish communication between said suction port and said evacuation port in the inoperative position of said sleeve board, and a separate passage therethrough in permanent communication with the vacuum line of said sleeve board, said last 70 passage opening downwardly through said valve

element in a location to register with said suction port when the sleeve board is swung to operative position.

2. A vacuum spotting board comprising a base, an upright vertically adjustable standard comprising telescopically disposed hollow sections supported on said base, and a pair of spotting boards supported by said adjustable standard, vacuum lines being associated with said respective boards to draw moisture therethrough, said sections jointly defining a chamber internally of said standard, a seal being interposed between the adjacent walls of said sections to render said chamber fluid tight while permitting relative movement of said sections, means for maintaining said sections in any desired position of adjustment, means communicating with said chamber above the bottom thereof for creating a suction therethrough, the upper end of said chamber being defined by a valve plate extending across the upper end of one of said sections and formed with a medial suction port therethrough, a valve element being swingable across said plate to selectively establish communication between said suction port and the vacuum lines of either of said boards, said chamber defining a trap for moisture entering same through said suction port, and a drain cock communicating with said chamber to remove the accumulated moisture therefrom.

3. In a vacuum spotting board, a supporting base, a standard projecting upwardly from said base, a vacuum chamber formed in said standard and means for maintaining a partial vacuum in said chamber, a horizontal valve plate extending across the upper end of said standard and having a suction port therethrough communicating with said chamber, a main spotting board having a vacuum line operatively associated therewith, an upper valve plate mounted in spaced parallel relation above said lower valve plate, an evacuation port being formed through said upper plate in vertical registry with the suction port in said lower valve plate, the vacuum line for said main board communicating with said evacuation port, in combination with a valve element pivotally mounted between said plates for swinging movement across said ports, a sleeve board carried by said valve element for swinging movement therewith between an operative position above said main board and an inoperative position out of vertical registry with said main board, said valve element having a fluid passage disposed therethrough in a location between said ports in the inoperative position of said sleeve board, and a separate passage therethrough in communication with the vacuum line of said sleeve board, said passage opening downwardly through said valve element in a location to register with said suction port when the sleeve board is moved to operative position.

4. In a vacuum spotting board of the class wherein a sleeve board is swingable to and from an operative position in relation to the main board, and both of said boards are provided with suction lines for drawing fluids therethrough, the combination with said boards of a support having a pair of ports and adapted to provide a bearing for a movable valve element, a source of suction in fixed communication with one port, the other port being in communication with the suction line of said main board, said valve element being disposed and movable in said support and having a passage means therethrough for registry with the respective ports to estab-

lish communication therebetween thereby providing suction for the main board, and a hollow supporting arm for said sleeve board mounted on said valve element for movement therewith, said valve element having a sleeve board passage and opening therein to register with the suction line port when said sleeve board is swung to operative position, said hollow supporting arm establishing communication between said sleeve board passage and the vacuum line of the sleeve board.

5. A vacuum spotting board comprising in combination a main spotting board and a sleeve board mounted above said main spotting board and swingable with respect to the main board into and away from an operative position, each of said boards being provided with a vacuum line for drawing fluids therethrough, a source of vacuum, a three-way valve connected between said source of vacuum and said vacuum lines, a movable valve element in said valve which in one position selectively serves to connect said source of vacuum to one of said vacuum lines while the other line is shut off, while in another position it serves to connect said source of vacuum to the other of said vacuum lines, said sleeve board being movable with and mounted on said valve element in such position that when the sleeve board is swung into its operative position the movable valve element connects the source of vacuum to the vacuum line of the sleeve board and when the sleeve board is swung into its inoperative position the movable valve element connects the source of vacuum to the vacuum line of the main board.

6. A vacuum spotting board comprising in combination a supporting base, an upright vertically adjustable tubular standard comprising telescopically disposed hollow sections forming a vacuum chamber, means for maintaining a partial vacuum in said chamber, a main spotting board mounted on said standard, a sleeve board also mounted on said standard above said main board and swingable into and away from an operative position, each of said boards being provided with vacuum lines for drawing fluids therethrough, a three-way valve connected between said vacuum chamber and said vacuum lines, a movable valve element in said valve adapted selectively to connect said vacuum chamber with one of said vacuum lines while the other line is shut off, the said sleeve board being movable with and mounted on said valve element in such position that when it is swung into its operative position the valve element thereby connects the vacuum line of the sleeve board to the vacuum chamber and that when it is swung into its inoperative position the valve element connects the vacuum chamber to the vacuum line of the main board.
